(57) **CLAIM**

The ornamental design for an offset door pull, as shown and described.

DESCRIPTION

FIG. 1 is a top, front, right side perspective view of an offset door pull according to our new design;
FIG. 2 is a top, rear, left side perspective view thereof;
FIG. 3 is a front elevation view thereof;
FIG. 4 is a rear elevation view thereof;
FIG. 5 is a right side elevation view thereof;
FIG. 6 is a left side elevation view thereof;
FIG. 7 is a top plan view thereof;
FIG. 8 is a bottom plan view thereof; and,
FIG. 9 is a cross-sectional view taken along line 9-9 of FIG. 3.

The offset door pull is shown with dashed break lines representing a symbolic break in its length, with the brackets adjacent the dashed break lines forming no part of the claimed design, and instead indicate that the appearance of any portion of the offset door pull between the dashed break lines forms no part of the claimed design. The short dash-short dash broken lines show portions of the offset door pull that form no part of the claimed design. The long dash-short dash broken lines represent boundaries of the offset door pull and form no part of the claimed design.
